CLAIM

The ornamental design for an electrical connector receptacle, as shown and described.

DESCRIPTION

FIG. 1 is a perspective view from a top front side of an electrical connector receptacle showing our new invention.

FIG. 2 is a perspective view from a top rear side thereof.

FIG. 3 is a perspective view from a bottom front side thereof.

FIG. 4 is a rear elevation view thereof.

FIG. 5 is a front elevation view thereof.

FIG. 6 is a left side elevation view thereof.

FIG. 7 is a right side elevation view thereof.

FIG. 8 is a top elevation view thereof; and,

FIG. 9 is a bottom elevation view thereof.

The broken line showing of the environment is for illustrative purposes only and forms no part of the claimed design.
